(57) **CLAIM**

The ornamental design for a rotary cheese grater as shown and described.

DESCRIPTION

1. Rotary cheese grater

1.1 : Perspective

1.2 : Perspective

1.3 : Front

1.4 : Back

1.5 : Left

1.6 : Right

1.7 : Top

1.8 : Bottom

1.9 : Perspective view of another state

1.10 : Perspective view of another state

1.11 : Exploded

The parts shown by means of broken lines in the reproductions are not part of the claimed design.
